UNITED STATES PATENT OFFICE.

THOMAS WHITE RATSEY, OF COWES, ASSIGNOR OF TWO-THIRDS TO EDWIN LAPTHORN, GEORGE ROGERS RATSEY, AND EDWIN WALTER LAPTHORN, OF GOSPORT, ENGLAND.

SAIL FOR VESSELS.

SPECIFICATION forming part of Letters Patent No. 517,193, dated March 27, 1894.

Application filed March 20, 1893. Serial No. 466,856. (No model.)

To all whom it may concern:

Be it known that I, THOMAS WHITE RATSEY, a subject of the Queen of Great Britain, residing at Cowes, Isle of Wight, England, have 5 invented certain new and useful Improvements in Sails, of which the following is a specification.

One of the principal objections to sails as heretofore made has been directly due to their 10 stretching out of shape and becoming too large for their spars. At one time, in order to allow for stretching, the spars were made larger than the edges of the sail, but as is now the usual practice, the sail must cover 15 the spars from end to end, without any allowance whatever being made for stretching. It is, therefore, necessary to have a sail which will fit spars from the start, and stand as well after long continued use as at first, in order 20 to obviate the necessity of continually stretching the sails to get them back into shape. It is well known that the greatest stretching takes place in the direction of the warp length- 25 wise of the cloth, while there is little—if any—stretching in the direction of the weft; and conversely, the shrinkage in the direction of the weft is also much less than in the direction of the warp. In the ordinary diagonal 30 sails the cloths or warp run with the leech and foot, but in my improved form of sail, I 35 arrange the cloths or warp at right angles to both the leech and foot, and at the beginning make each sail the full length of its respective spar; and my invention consists in the features and details of construction hereinafter described and claimed.

In the drawings, Figure 1 is a diagrammatic view representing the various sails of a boat in side elevation; and Figs. 2 and 3 show different ways of attaching the topsail.

In making my improved sail, I take two or more pieces A and A', of any fabric used or which may be used for sails, and join them by sewing or otherwise, in such manner that 45 the warp stands at right angles to the leech C and foot C' of the sails. This forms a sail having a diagonal seam, the warp of the piece A arranged to run at right angles to the leech C, while the warp of the piece A' stands at 50 right angles to the foot C'. By these means the fabric is prevented from stretching, inasmuch as the weft runs parallel with the leech

and foot. As there is practically no stretch in the weft of any sail cloth, it follows that these sails cannot stretch, as other diagonal 55 sails which have the warp (which stretches very much) parallel to the leech and foot. Furthermore, owing to the non-shrinkage of the weft of any sail cloth, it is obvious that the improved diagonal sails cannot shrink on 60 the leech or foot. On this account, the sails may be made to the full length of their respective spars, and do not require stretching to get them back into shape to fit the spars. The many advantages hereinbefore recited 65 will be readily apparent to any one skilled in the art of sail making, or having any knowledge of the use of sails.

The invention is applicable for mainsails, 70 lugsails,trysails,jibs of all descriptions, fore-sails, staysails, mizzens, and topsails of all descriptions, and as mentioned before, the sails in each instance can be made at the start to the full size of the spars.

I claim—

1. As a new article of manufacture, a sail made in several portions, the warp of the fabric of some of such portions standing perpendicular to the leech, and the warp of the other portions standing perpendicular to the 75 foot, substantially as described.

2. As a new article of manufacture, a sail made in two portions, the warp of the fabric of one portion standing perpendicular to the leech and the warp of the fabric of the other 80 portion standing perpendicular to the foot whereby stretching of the sail is prevented, substantially as described.

3. As a new article of manufacture, a sail constructed in two portions and having a diagonal seam, the warp of the fabric of one portion standing perpendicular to the leech, and the warp of the fabric of the other portion standing perpendicular to the foot, whereby stretching of the sail is prevented, sub- 85 stantially as described.

February 7, 1893.

THOMAS WHITE RATSEY.
